THOMAS C. SHEEHAN, OF UPPER MONTCLAIR, NEW JERSEY, ASSIGNOR TO DURHAM
DUPLEX RAZOR COMPANY, A CORPORATION OF NEW YORK

SAFETY RAZOR

Application filed March 3, 1931. Serial No. 519,809.

This invention relates to an improved safety razor of the type in which the guard which engages one side of the blade is provided with blade abutments, its main object 5 being to provide improved means for locking the blade and guard together and means for simultaneously aligning the cutting edge of the blade against said abutments.

In safety razors of this type it is highly 10 desirable that the blade be accurately aligned with the blade abutments to place the cutting edge in proper position for shaving. By providing means for aligning the blade while it is being locked to the guard, the cutting 15 edge is placed in the proper position from which it cannot be displaced without unlocking the guard. With this and other objects not specifically mentioned in view the invention consists in certain constructions and 20 combinations which will be hereinafter fully described and then specifically set forth in the claims hereunto appended.

In the accompanying drawing which forms a part of this specification and in which like 25 characters of reference indicate the same or like parts:

Fig. 1 is a side elevation of the improved safety razor;

Fig. 2 is a top view of the same;

30 Fig. 3 is a bottom view of the razor with the clamp plate removed but with the razor blade in locked position;

Fig. 4 is a bottom view similar to Fig. 3, but with the razor blade in unlocked position;

Fig. 5 is a sectional side elevation of the assembled razor, taken on line 5—5 of Fig. 2;

40 Fig. 6 is a lengthwise section through the assembled razor, taken on line 6—6 of Fig. 1;

Fig. 7 is a side elevation of the razor clamp plate assembled with the blade;

Fig. 8 is a top view of the same; and

Fig. 9 is a plan view of the razor blade.

In carrying the invention into effect, there 45 is provided a slotted blade, a clamp engaging one side of the blade, a guard having blade abutments and engaging the other side of the blade, a locking member for locking said blade between said clamp and guard, 50 said member including a yielding cam for

engaging the slot in the blade for aligning its cutting edge against said abutments. In the best constructions contemplated the clamp is provided with headed pins projecting through the slot in the blade, and the locking member includes a disc rotatably mounted on the guard to engage the heads of the pins and provided with recesses for releasing the pins when the locking member is fractionally rotated from locking position, and said locking member is provided with angularly disposed handle sockets to enable the razor to be used like an ordinary safety razor or like a straight razor. In the preferred form of construction, the yielding cam and the disk 65 and handle sockets are rigidly connected together, and the cam is split axially to permit the portion of the same which engages the slot in the blade to yield when its cutting edge engages the abutments, whereby to prevent injury to the cutting edge.

Referring to the drawing, the slotted razor blade 1 of well known construction has a guard 2 engaging one side of the blade and a clamp 3 engaging its other side. The guard 2 is provided with suitable studs which loosely engage the ends of the slot in the blade and fit openings provided in the clamp 3. There is rotatably mounted in the guard 3 a locking member comprising a disc 4 fitted into a recess in the inner side of the guard and having diametrically opposite recesses 5 which may be moved into registry with openings 6 in the guard 2. The clamp 3 is provided with headed pins 7 which project through the blade with their heads entering the perforations 6 so that the under side of the heads may be engaged by the disc 4 to lock the blade between guard 2 and clamp 3. 75 When the recesses 5 of the disc are moved into registry with the openings 6 in the guard the pins 7 of the clamp 6 may be withdrawn therefrom and the blade removed.

The locking member also includes a yielding cam 8 and a head 9 which are rigidly connected to the hub of the disc 4 by any suitable means such as a pin as shown. The cam 8 is fitted into the hub of the disc 4 and provided with a head having a cam portion 90 100

10 which is adapted to engage one edge of the blade slot to align one of its cutting edges with the abutments 11 on one edge of the guard 3. To prevent injury to the cutting 5 edge while it is being aligned with the abutments, the cam 8 is split axially to permit the cam portion 10 to yield, when the cutting edge engages the abutments.

10 The head 9 is provided with two threaded handle sockets 12 which are adapted to receive the threaded portion of the handle 13, and are angularly disposed with respect to each other to permit the razor to be used like an ordinary safety razor or like a 15 straight razor.

20 When the handle is moved to engage the disc 4 with the headed pins 6 the blade 1 is locked between the guard 2 and clamp 3, simultaneously aligning one of its cutting edges with the abutments 11 on one edge of the guard. To remove the blade the disc 4 is fractionally rotated through an angle of 90 degrees by moving the handle so that the recesses 5 in the disc register with the openings 6 in the guard, thereby permitting the 25 clamp and blade to be removed.

30 In view of the foregoing description of the device it will be observed that the razor blade is locked between the clamp and guard by a quarter turn of the locking member, thereby obtaining an appreciable saving of time as compared with known devices of this type.

35 What is claimed is:

35 1. A safety razor comprising a blade, a guard engaging one side of said blade and having blade abutments, mechanism including a rotatable member for locking said blade and said guard together, and a yielding cam actuated by said member and engaging said blade to move it transversely and align its cutting edge against said abutments.

40 2. A safety razor comprising a perforated guard having blade abutments, a head rotatably mounted on said guard, a handle threaded into said head, a slotted blade, a clamp adapted to clamp said blade to said guard, headed pins on said clamp projecting through the slot of said blade into the perforations of 45 said guard, a disc fixed to said head and having diametrically opposite recesses to permit the passage of the heads of said pins, and a yielding cam fixed on said head and adapted to engage one edge of the slot in said blade whereby fractional rotation of said head by 50 means of said handle will cause said disc to lock the pins on said clamp in the perforations in said guard and simultaneously align one edge of the blade against said abutments.

55 3. A safety razor comprising a blade having a cutting edge on each longitudinal edge, a guard engaging one side of said blade and having a set of blade abutments adjacent each cutting edge of the blade, mechanism for 60 locking said blade and said guard together,

and a yieldable device actuated by said mechanism for moving the whole blade transversely toward either set of abutments to align either cutting edge of said blade against said abutments.

65 4. A safety razor comprising an apertured blade having a cutting edge on each longitudinal edge, a clamp engaging one side of said blade, locking means carried by said clamp and projecting through said blade and having a set of blade abutments adjacent each cutting edge of the blade, a guard engaging the opposite side of said blade, a locking member rotatable in said guard and 70 engaging said means and releasable therefrom when fractionally rotated, and a device operated by said member for moving the whole blade transversely toward either set of abutments to align either cutting edge of 75 said blade against said abutments.

80 5. A safety razor comprising an apertured blade, a clamp engaging one side of said blade, locking means carried by said clamp and projecting through said blade, a guard engaging the opposite side of said blade, a locking member rotatable in said guard and 85 engaging said means and releasable therefrom when fractionally rotated, and a yielding cam actuated by said member for moving the blade transversely to align the cutting 90 edge of said blade.

95 In testimony whereof, I have signed my name to this specification.

100 THOMAS C. SHEEHAN.
